(57) **CLAIM**

The ornamental design for a filtration mask as shown and described.

DESCRIPTION

FIG. 1 is a top perspective view of a filtration mask showing my new design;

FIG. 2 is a front elevational view thereof;

FIG. 3 is a rear elevational view thereof;

FIG. 4 is a left side elevational view thereof;

FIG. 5 is right side elevational view thereof;

FIG. 6 is a top plan view thereof; and

FIG. 7 is a bottom plan view thereof.

The broken lines in the drawings illustrate portions of the article that form no part of the claimed design.

1 Claim, 6 Drawing Sheets
